LUMINOUS FLAME FURNACE

Paul K. Richardson, Salt Lake City, Utah, assignor to American Smelting and Refining Company, New York, N. Y., a corporation of New Jersey

Application June 27, 1939, Serial No. 281,342

3 Claims. (CL. 263—52)

This invention relates to the construction and operation of gas-fired furnaces.

Among other features, the invention provides an improved burner arrangement through the use of which luminous flame temperatures in excess of 2500° F. are readily attained using natural gas as the source of fuel.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a vertical section through a metallurgical furnace of the reverberatory type provided at its firing end with the novel burner arrangement of the invention;

Fig. 2 is a view taken along the line 2—2 of Fig. 1; and

Fig. 3 is an end view of the same furnace at its firing end showing the burner arrangement.

Like reference characters denote like parts in the several figures of the drawings.

Referring to the drawings, 10 indicates a reverberatory furnace of the type commonly employed in dross and copper smelting operations, the firing end only being shown as the remainder of the furnace may be of any standard construction. Adjacent the firing end of the furnace proper and substantially integral therewith is the firing structure and system designated generally by 12 and comprising an ignition chamber 14, a cracking chamber 16 and passageway 18 leading from the chamber 16 to the firing throat 20.

An arch 22 with checkered passageways 24 separates the chambers 14 and 16 and permits gas flow from the former into the latter. Chamber 14 is provided with a heating burner 26 and chamber 16 is equipped with a duct 28 branching into air pipe 30 and raw gas pipe 32. These pipes are provided with valves 34 and 36, respectively. A main air pipe 40 and natural gas pipe 42 supply the fuel mixture for the pair of premix burners 38 which are directed toward the throat 20 of the furnace.

In operating the furnace, a mixture of natural gas and air which will yield a neutral flame upon combustion is supplied to burner 26. The resulting hot gases pass upwardly from the ignition chamber 14 through the openings 24 in arch 22 into the cracking chamber 16 into which also flows raw natural gas supplied by the duct 28

from pipe 32. Inasmuch as the hot gases entering the chamber 16 from the ignition chamber 14 are non-oxidizing, there is effected a cracking of the raw natural gas introduced by duct 28 and the resulting mixture passes from the chamber 16 through the passageway 18 into the path of the gases from the premix burners 38 thereby yielding a highly calorific gas with sufficient free carbon to impart a high degree of luminosity to the flame entering the furnace through throat 20. Carbon deposits or accumulations in the cracking chamber 16 are readily removed simply by closing valve 36 and opening air valve 34 for a few minutes.

It will be apparent that the present invention provides definite advantages. Thus, by cracking a portion of the primary fuel to produce the luminous flame without the use of preheated air which makes for imperfect cracking and gas dilution, the ultimate gaseous mixture is of high calorific value and results in high emissivity and high flame temperature being readily attained with low furnace volume. Further, the construction of the cracking chamber and all cooperating parts as a compact and substantially integral part of the furnace proper not only conserves space but reduces radiation and infiltration losses, as well as maintenance costs, to a minimum.

30 While various specific disclosures have been made for illustrative purposes, it will be understood that various modifications, substitutions and changes are embraced by the invention which is defined in the appended claims.

35 What is claimed is:

1. The process for firing a furnace with a highly luminous flame which comprises burning natural gas to produce substantially neutral, hot combustion gases, introducing raw natural gas 40 into said combustion gases to effect cracking of the raw gas, conducting the resulting mixture into the path of a main mixture of natural and combustion-supporting gases to form a final fuel mixture, and introducing the latter into the heating chamber of the furnace thereby producing a high temperature, luminous flame therein.

2. The process for operating a furnace of the reverberatory type which comprises firing the furnace with a first mixture of natural gas and air directed into the main furnace chamber containing the material to be heated, burning a second mixture of natural gas and air in a chamber separate from the main furnace chamber to produce hot, substantially neutral combustion gases, conducting said combustion gases to and into the

path of said first gas mixture, and introducing raw natural gas into said combustion gases prior to their intermixing with said first mixture of natural gas and air in order to crack said raw natural gas, whereby a highly luminous flame is produced in the main furnace chamber.

3. The combination with a gas-fired furnace having a firing throat and burner means for supplying a combustible gas-air mixture to said throat, of an auxiliary chamber at the firing end 10 of said furnace and positioned below said firing

throat, a horizontally-disposed, perforated arch interiorly dividing said chamber into a lower ignition compartment and an upper cracking compartment, the top of the latter compartment opening into the firing throat of said furnace, means for supplying hot, substantially neutral combustion gases to said ignition compartment, and means for introducing raw natural gas into said cracking compartment.

PAUL K. RICHARDSON.
